(57) **CLAIM**

The ornamental design for a corner insert for an insulated container, as shown and described.

DESCRIPTION

FIG. 1 is a perspective view of my new ornamental design for a corner insert for an insulated container as installed in a container.

FIG. 2 is a perspective view of the corner insert shown in FIG. 1.

FIG. 3 is a front view of the corner insert shown in FIGS. 1 and 2.

FIG. 4 is a back view of the corner insert shown in FIGS. 1-3.

FIG. 5 is a top view of the corner insert shown in FIGS. 1-2. The bottom view is the mirror image of the view shown in FIG. 5; and,

FIG. 6 is an end view of the corner insert shown in FIGS. 1-5.

Opposite end view is a mirror image of the view shown in FIG. 6.

The broken line showing of a container and additional inserts is for illustrative purposes only and forms no part of the claimed design.
